(57) **CLAIM**

I claim the ornamental design for a wedge hinged container, as shown and described.

DESCRIPTION

FIG. 1 is a perspective view of a wedge hinged container showing my new design, in partially opened condition;

FIG. 2 is a perspective view thereof, in closed condition;

FIG. 3 is a side elevation view thereof, in fully opened condition;

FIG. 4 is a top plan view thereof, in fully opened condition; and,

FIG. 5 is a bottom plan view thereof, in fully opened condition.
